COOL SMOKING PIPE

Mariano La Barbera, New York, N. Y.

Application December 16, 1936, Serial No. 116,097
Renewed March 3, 1938

5 Claims. (Cl. 131—12)

This invention relates to new and useful improvements in a cool smoking pipe.

The invention has for an object the construction of a smoking pipe which is characterized by a pipe stem with a novel construction which produces a cool smoke when the pipe is used.

More specifically, the invention contemplates an arrangement of a pipe stem formed of sections, one connected with the bowl and the others with the mouthpiece of the pipe stem. It is proposed to arrange the junction between these sections in a particular manner.

It is proposed to provide inter-engaging portions on the adjacent ends of the pipe sections and to arrange longitudinal recesses along the sides of one of the sections, and communicating with radial recesses connecting with a passage for the smoke through the mouthpiece. When the smoke is caused to travel through this path it will be relatively dry and cool.

Still further the invention proposes to provide an element rotative on a reduced portion of the mouthpiece stem section which is to be formed with V-shaped passages connecting with a main smoke passage, to provide longitudinal passages in the outer face of said element connecting with radial passages aligned with portions of said V-shaped passages and to provide an arrangement whereby the element may be held in various turned positions to control the alignment of the radial passages with the V-shaped passages and thus the passage of smoke.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a transverse sectional view of a pipe constructed according to this invention, a portion thereof being shown in side elevation.

Fig. 2 is a perspective view of the mouthpiece stem section per se.

Fig. 3 is a transverse sectional view of a portion of the mouthpiece stem section, this section being taken on the line 3—3 of Fig. 1.

Fig. 4 is a fragmentary horizontal sectional view taken on the line 4—4 of Fig. 2.

Fig. 5 is a developed view of the reduced portion of the mouthpiece stem section.

Fig. 6 is a sectional view of a pipe constructed according to another embodiment of this invention.

The smoking pipe, according to this invention, comprises a pipe bowl 10 connected with a bowl stem section 11 formed with a passage 12 for the smoke. The bore of the pipe bowl 10 is formed with a substantially flat bottom 13. There is a small aperture 14 in one side of the bottom 13 which connects with the bottom of the passage 12, which is relatively much larger in size than the opening 14. A mouthpiece stem section 15 supports an element 16 which is engageable into the end of the passage 12 for connecting the sections together. The element 16 may be rotative upon a reduced portion 15^a of the mouthpiece stem section 15. This reduced portion 15^a is formed with V-shaped passages 17 connecting with a main smoke passage 28 which is preferably round in cross section, and extends through the mouthpiece stem section. The V-shaped passages 17 are arranged circumferentially on the peripheral surface of the reduced portion 15^a. 20

Longitudinal passages 18 are formed on the outer face of the element 16 below the center of said element and connect with radial passages 19 aligning with portions of the V-shaped passages 17. A means is provided for holding the element 16 in various rotative positions to control the alignment of the radial passages 19 with the V-shaped passages 17. The full lines in Fig. 5 show relative positions of these parts in which the passage is completely unrestricted. The dot and dash circles 19' indicate different positions of the passages 19 in which there is some restriction. It should be noted that the element 16 may be turned to various positions to produce various different sizes of passages for the smoke. 30 35

The means for holding the element 16 in various rotative positions includes a resilient element such as a spring 20 which is coaxially arranged upon the reduced portion 15^a and which acts against a shoulder 16^a formed in the reduced portion 16. The spring 20 also acts against a flange 21 which is fixedly mounted upon the outer end of the reduced portion 15^a. A plug 22 closes the inner end of the passage 18 so that the smoke is forced to pass through the longitudinal passages 18 through the radial passages 19 and then through the main smoke passage 28 formed in the mouthpiece stem section 15. The spring 20 urges the element 16 so that an end portion 16^b formed engages against a portion of a shoulder 15^b formed on the mouthpiece stem section 15. These engaging surfaces may be roughened or serrated so that they readily maintain relative positions. 40 45 50

In Fig. 6 another embodiment of the invention 55

has been disclosed in which the mouthpiece stem 15' and the reduced portion 15^{aa} are separate pieces connected by a threaded portion 15''. In other respects this form of the invention is similar to the previous form and similar parts may be recognized by the same reference numerals.

The operation of the device is as follows:— When smoke is drawn through the mouthpiece it will travel from the pipe bowl 10 through the passage 14, the passage 12, the longitudinal passages 18, the radial passage 19, and the passage 28 to the smoker's mouth. The element 16 may be turned relative to the mouthpiece 15 for a dual purpose. First, to control the alignment of the passages 18 with the passages 17, and thus the passage of smoke. Then again, the element 16 may be turned to different positions to change the relative positions of the longitudinal passages 18 to the base of the passage 12. This will control to some degree the amount of moisture permitted to pass through the pipe stem.

It is to be understood that this invention may be used in connection with all types of smoking pipes, irrespective of their shapes or material they are made of.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

1. In a smoking pipe, a pipe stem comprising a bowl stem section with a passage for smoke and a mouthpiece stem section having an element engageable into said passage for connecting said sections together, said element having radial passages and being slidably supported on a reduced portion of said mouthpiece stem section, longitudinal passages on the outer face of said element connecting with said radial passages, said longitudinal passages being located below the center of the said reduced portion.

2. In a smoking pipe, a pipe stem comprising a bowl stem section with a passage for smoke and a mouthpiece stem section having an element engageable into said passage for connecting said sections together, said element having radial passages and being rotatively supported on a reduced portion of said mouthpiece stem section which has V-shaped passages connecting with a main smoke passage, longitudinal passages on the outer face of said element connecting with said radial passages aligning with portions of said V-shaped passages, and means for holding said element in various rotative positions to control the align-

ment of said radial passages and said V-shaped passages.

3. In a smoking pipe, a pipe stem comprising a bowl stem section with a passage for smoke and a mouthpiece stem section having an element engageable into said passage for connecting said sections together, said element having radial passages and being rotatively supported on a reduced portion of said mouthpiece stem section which has V-shaped passages connecting with a main smoke passage, longitudinal passages on the outer face of said element connecting with said radial passages aligning with portions of said V-shaped passages, and means for holding said element in various rotative positions to control the alignment of said radial passages and said V-shaped passages, said longitudinal passages comprising passages on opposite sides of said element.

4. In a smoking pipe, a pipe stem comprising a bowl stem section with a passage for smoke and a mouthpiece stem section having an element engageable into said passage for connecting said sections together, said element having radial passages and being rotatively supported on a reduced portion of said mouthpiece stem section which has V-shaped passages connecting with a main smoke passage, longitudinal passages on the outer face of said element connecting with said radial passages aligning with portions of said V-shaped passages, and means for holding said element in various rotative positions to control the alignment of said radial passages and said V-shaped passages, comprising a resilient element acting against a shoulder portion formed on said element and a flange portion mounted on said reduced portion.

5. In a smoking pipe, a pipe stem comprising a bowl stem section with a passage for smoke and a mouthpiece stem section having an element engageable into said passage for connecting said sections together, said element having radial passages and being rotatively supported on a reduced portion of said mouthpiece stem section which has V-shaped passages connecting with a main smoke passage, longitudinal passages on the outer face of said element connecting with said radial passages aligning with portions of said V-shaped passages, and means for holding said element in various rotative positions to control the alignment of said radial passages and said V-shaped passages, comprising a resilient element acting against a shoulder portion formed on said element and a flange portion mounted on said reduced portion, said resilient element serving to force an end of said element against a shoulder on said mouthpiece stem section, said resilient element comprising a coaxial spring mounted on said reduced portion.

MARIANO LA BARBERA.
